ELECTRIC SIGN

Application filed May 21, 1927. Serial No. 193,214.

This invention relates generally to signs, and more especially to advertising display signs illuminated by electricity; and has for its main object means whereby a sign may be made up from separate units, of interchangeable parts, each unit containing one or more characters, and adapted to be changed as may be required.

Other objects will appear as the description proceeds.

These objects are obtained by the methods and means here described, and illustrated in the accompanying drawing, in which—

Figure 1 is a partly cut-out perspective view of two of the plurality of the separable units comprising the sign, arranged in operative relation in their common support; and Fig. 2, a multiple cross-sectional view from above, in somewhat reduced scale, showing further details of construction—the base details at the left, and the container wall details at the right.

Similar numerals refer to similar parts throughout the several views.

The part numbered 1 is a common supporting member for a plurality of the sign units 2. It consists of a trough-shaped member of suitable material, usually non-corrosive metal, cut off to a length to hold any desired number of the sign units 2.

The individual units 2, being all alike, are interchangeable, and they are made to have electrical contact with each other, to make a circuit for lighting the electric light bulbs contained in each one, by merely positioning them in the holder 1 adjacent each other. This is accomplished by the construction of the unit base, which consists of an insulated member 3 formed to a shape somewhat as shown, and having along its opposite sides two parallel recesses, into which conducting bars or contact pieces 4, are positioned. These contact pieces have their ends projecting from one end of base 3, and are bent at their opposite ends, as shown in Fig. 1, to form a resilient recess to retain and make electrical contact with the projecting ends of adjoining sign units. Contact pieces 4 are formed with an inwardly-projecting centrally-disposed arm which, in one case, ends

in an essentially semi-circular shaped contact 5, shown in the cross-sectional view at the left of Fig. 2, while that of its companion bar 4 has its projection consisting simply of a straight arm 6, positioned as shown. Thus the positive current is conducted through one of the contact bars, and the negative current through the other, and the light bulb 7 is arranged to be positioned "in series" across the line by having the two terminals of its base make contact, respectively, with the contact arm 6 and the semi-circular arm 5. The threaded base of bulb 7 is screwed into a similarly-threaded metallic shell, 8, having bottom flanges as shown in Fig. 2, which secures it to the base 3 by means of small rivets passing through it and the contact arm 5 above, into said base.

The bulb 7, with a portion of base 3, is surrounded by a sign-housing 2, of the form shown in Fig. 1. In the specific embodiment, this consists of a piece 9 of separating insulating material, such as fibre, fitting down over the base, and containing an opening through which protrudes the projecting part of the base which surrounds the bulb, a flat metallic sheet or cap member 10, with flanged-down sides, also similarly positioned, and a flat arched metallic member 11 positioned over parts 9 and 10, and holding them in place, it in turn being secured to the base 3 by means of bolts or other fastening means, 12.

The side wall member 13 of the container consists of a piece of flat metallic material, in the present embodiment bent so as to form the two side walls, and having an arched portion which serves as the top of the container. Lugs are struck out of the lower side of member 13, and these, when the unit is completely assembled, rest beneath the nuts 12, thus holding member 13 rigidly upright on base 3. The upright edges of member 13 have a small right-angle flange as clearly shown in the sectional view at the right of Fig. 2.

The front and back faces of the complete unit 2 consist essentially of an interchangeable slide frame 14, having a large aperture and shaped in outline as shown in Fig. 1, and in section as shown at the right in Fig. 2, this

section being of channel shape. It is also usually formed from sheet metal, plated or otherwise coated for the sake of appearance. Its bottom end is open so that it is adapted to slide up and down the flanged edges of side members 13, and be removed therefrom. Sufficient space is provided so that there can be positioned within the channel section of slide 14 a flat colored screen or plate 15, and a glass plate 16, on one face of the unit. Plate 16 may be transparent or translucent over one portion of its surface to designate a letter or other character, such as the "X" shown in Fig. 1, the remaining area of the plate being opaque, to exclude the passage of light. Thus the plate serves as a sign, the illumination only coming through to show the desired character.

The back slide 14 usually encloses only a back plate 17. This may be perforated, as shown at 18, for purposes of ventilation. However, in lieu of the back plate, a sign plate may be used here also, thus forming a plural-faced sign. Again, this back plate may hold merely the color screen to give a footlight effect to the sign background.

As a means of retaining the adjacent sign units rigidly in an upright position in their common support 1, a separating member 19, Fig. 1, is positioned between adjacent sides thereof, this member being U-shaped in cross-section, the U being reversed so that the connecting lower part is the upper part of the member, as shown. This member is of sufficient width to fit between the adjacent side members 13 of the sign unit, and of sufficient depth to slide between the front and back slide members 14 of each unit.

The screen member 15, as here used, consists of a flexible piece of wire gauze with a coating of translucent coloring material.

The operation of the device is as follows:

A plurality of these sign units 2 are slid into their trough-shaped support 1 and forced into adjacent position with each other so that electrical contact is made, one with the other, as previously explained. Separating members 19 are then put in position. The end contacts are then connected to a suitable source of electrical current to light up all the bulbs. With each set of sign units is a plurality of glass plates 16, having, for instance, the various letters of the alphabet, figures, and other designations as needed. These are sufficient in number to make possible, by changing them in adjoining units, any series of words, with proper spaces, to form a complete illuminated advertising sign, as, for instance, to advertise the program of a theatre. The reading of the sign may be changed at will by merely sliding out the slides 14 in each unit, removing sign plates 16, and substituting therefor other plates with different letters or characters to form different words with the adjoining

units. Moreover, the sign may be shortened or lengthened as needed, by building it up with less or more units, thus effecting advantages such as economy in current consumption. In the event of accidental breakage, the broken unit only need be taken out and replaced, and as each unit consists of many separable and interchangeable parts, the damaged parts requiring replacement may be further limited. Different color combinations in adjacent units may be effected by using different color screens. Thus the initial letters of all words may be in red, or the most important word in a sign in yellow. The units may be instantly disassembled and assembled without the use of tools, or without making any electrical contacts whatever, the mere positioning of the units side by side accomplishing this automatically.

It is to be understood that the present disclosure is for the purpose of illustration only, and that the invention is not limited thereto. To those skilled in the art, many modifications of the invention will be readily apparent, and it will also be obvious to such skilled persons that part of the device may be used without other parts thereof, many such combinations of the parts readily suggesting themselves. Therefore, it should be, and is to be distinctly understood that for a definition of the limitations of the invention, reference must be had to the appended claims.

Having now described the invention, what is new and for which it is desired to obtain Letters Patent of the United States, is:

1. In combination in a sign unit, an insulated base, a plurality of conducting members positioned therein, inwardly extending projections on said members co-acting to make contact with the terminals of an electric light bulb, and a container surrounding the bulb and having a replaceable sign element, the contact elements projecting from one end of the base, and recessed into its other end, and adapted to form electrical contact with adjoining units by their mere juxtaposition.

2. In combination, a base, contact elements therein, insulating means projecting from the upper surface of the base and surrounding the base of light means, a cover plate over the base and surrounding the light means, and an enclosing member therearound and secured to the base, including sliding front and back plates on said surrounding member, one of said plates being opaque, to outline a transparent character.

3. In combination, a channeled base and a plurality of sign units demountably held therein, each unit comprising a unit base, a light source secured thereto, an enclosing frame surrounding the light source and secured to the unit base, and a slidably holding member positioned along one side of the frame, and adapted to hold a transparent

sign plate, and within it, a colored light screen, both of which help to inclose the light source, there being a separating element between adjacent sign units, adapted to make contact therewith at a plurality of points above the base, to prevent mis-alignment longitudinally and laterally.

4. In combination a channel member, a plurality of sign units adapted to slide therein and to make electrical contact with each other, a light source in each sign unit, a slideable frame around the light source, and a spacing member adapted to slide between adjacent sliding frames to maintain them in alinement.

10 Signed at New York, in the county of New York and State of New York, this 16th day of May, A. D. 1927.
